UNITED STATES PATENT OFFICE.

WILLIAM E. WOLFE, OF RECLUSE, WYOMING.

KICKING BOOT.

Application filed July 31, 1923. Serial No. 654,864.

To all whom it may concern:

Be it known that I, WILLIAM E. WOLFE, a citizen of the United States, residing at Recluse, in the county of Campbell and 5 State of Wyoming, have invented certain new and useful Improvements in Kicking Boots, of which the following is a specification.

My invention relates to an anti-kicking 10 device for milk cows, or so-called "kicking boot." The object of the invention is to furnish a boot of this character that may be readily secured to the hind leg of a cow, and which is adapted to be attached around 15 the joint to prevent the bending of the leg and make it impossible for the cow to kick while being milked.

A further object of the invention is to construct the boot in a very simple and 20 effective form so that it may be manufactured at a low cost, and make it easy in application.

In the accompanying drawing, one embodiment of the invention is illustrated; 25 and—

Figure 1 represents a fragmentary side view of a cow with the boot in position;

Figure 2 is a perspective view of the boot; and

Figure 3 is an end view of a modified shape of the boot.

This boot consists of a piece of metal bent into channel shape and having a main central web 10 extending the full length 35 of the boot, and upturned flanges 11 which are lower at the middle of the boot, as at 12, and higher at each end thereof, as at 13. This makes a channel-shaped cross section of the boot, and the ends forming 40 wings extending further back along the leg of the cow, while the lower middle portion of the flanges 12 are very shallow, and the edge connecting the ends with this narrow portion is arcuate, as best seen at 18 in Figure 2, the ends 13 being well rounded 45 as at 19. The end edges of the flanges thus form substantially right angles with the central web 10 and the rounded edges run tangentially to said straight edges as well 50 as to the arcuate connecting edges of the flanges. In the middle of the central web 10 are provided a pair of parallel slits 14 directed longitudinally of the boot, and through these slits is slipped a strap 15 having a stout buckle 16 at one end thereof. The length of the strap 15 is sufficient to

go once around the leg of the cow and to firmly hold the boot thereon.

In applying the device to the animal, the boot is laid against the forward side of 60 the hind leg, as seen in Figure 1, and the width between the side flanges 11 is sufficient to readily accommodate the leg. The strap is now taken around the leg and passed through the buckle 16 so that the strap will 65 be situated immediately above the joint 17 of the cow's leg, as indicated in Figure 1. With the strap drawn up sufficiently tight, the bending of the leg at the joint is practically impossible, and when the cow finds 70 that she can only do this with difficulty and not without hurting herself, she will soon desist from attempts to kick over the milk bucket.

This shows the simplest form of 75 constructing the boot, but it is evident that slight variations may be made without deviating from the scope of the invention. For instance, instead of making the boot channel-shaped with square corners, a U- 80 shaped section might be selected with rounded central web 20, see Fig. 3, instead of the flat web 10, as indicated in Figure 2. The general character of the boot, however, has been found to be practical, that is to say, 85 with the shallow depth of the channel in the middle and a considerable depth at the ends thereof. The web 10 is perfectly straight in the length direction of the boot 90 and not bent.

In most existing boots of this class now 95 found on the market, much more complicated construction is to be seen, and most of these boots consist of three or more separate parts, which are generally hinged together and secured by means of a latch or several straps. In applicant's case, on the other hand, there is only one metallic channel-shaped piece, and one strap for securing the same to the animal's leg. Accordingly, it will only take a moment to attach 100 or detach the boot and the same can readily be shifted from one cow to another as it is entirely self-adjusting.

Having thus described the invention, 105 what is claimed as new is:

A boot of the class described comprising a metal body having a flat straight central web and flat straight side flanges turned back from said web, said flanges having a comparatively slight height midway their ends and considerably greater height at 110

each end thereof, and edges of arcuate contour between said ends and the middle portion of the flanges, said central web being provided with longitudinal slits between said flanges at its center, a flexible strap engaging through said slits and provided with fastening means, the body being adapted to fit against the front side of an animal's

leg across the joint therein with the side flanges embracing the leg and the strap being adapted to pass around the leg above the joint. 10

In testimony whereof I affix my signature.

WILLIAM E. WOLFE. [L. S.]
